UNITED STATES PATENT OFFICE.

WILLIAM E. MUNDAY, OF STATESVILLE, NORTH CAROLINA.

ELEVATING BENCH.

Application filed February 1, 1924. Serial No. 690,002.

To all whom it may concern:

Be it known that I, WILLIAM E. MUNDAY, a citizen of the United States, residing at Statesville, in the county of Iredell and

5 State of North Carolina, have invented certain new and useful Improvements in Elevating Benches, of which the following is a specification.

The present invention relates to elevating 10 benches, trucks, or cradles for motor vehicles and the like, and the objects and nature of the invention will be readily understood in the light of the following explanation of the accompanying drawings illustrating what I 15 consider to be the preferred mechanical expression or embodiment of my invention from among other forms, constructions, and arrangement within the spirit and scope of the invention as hereinafter claimed.

20 It is an object of this invention to provide a bench or truck of improved structure capable of holding and supporting a motor vehicle in an elevated horizontal position so that ample room is provided below the car 25 for inspection of and access to parts below the vehicle body; and to provide such truck or cradle of a type whereby the vehicle may automatically pivot the same to a horizontal position after having been run up the bench 30 35 when in an inclined position; and to provide means for holding the motor vehicle on the bench or truck in a stationary position.

Another very important object of the invention is to provide a device possessed of a light and durable structure which is strong 35 and may be readily assembled and disassembled.

The invention also contemplates a structure which may be manufactured at a comparatively small cost because of the simplicity of the various parts and which will yet be reliable, and well adapted to the purpose for which it is designed.

The invention comprises essentially parallel track ways pivotally mounted on supports in such a manner as to cause the track ways to assume a horizontal position by the weight of the vehicle as the latter is run thereon and means for maintaining said track ways in such position.

With the above and numerous other objects in view, my invention consists in certain novel features of construction, and in the combinations and arrangement as more fully and particularly set forth and specified hereinafter.

In the drawing:

Figure 1 is a side elevation of the apparatus embodying my invention,

60 Figure 2 is a top plan view thereof,

Figure 3 is a detail vertical section taken substantially on the line 3-3 of Figure 1 looking in the direction of the arrows,

Figure 4 is a detail perspective view showing one of the trackways inverted with an 65 end leg thereon,

Figure 5 is a perspective view of one of the main supports, and

Figure 6 is a detail fragmentary perspective of one of the track ways showing my 70 improved chuck associated therewith.

Referring to the drawings in detail it will be seen that the letter A designates the two main supports on which are adapted to be pivotally mounted the two trackways B. At 75 the ends of the trackways there are provided leg apparatus indicated generally at C. Each track way B has mounted thereon a pair of chuck members indicated generally at D.

80 The main supports A are constructed with bases 1 formed of angle iron and provided with side wings 2. A standard 3 rises from the base 1 and is also constructed of channel iron, the side plates thereof being beveled 85 at their upper ends so that the trackways may freely rock thereon.

The track ways B are formed of channel iron as is indicated at 4 and on an intermediate portion of the bottom thereof there 90 are disposed brackets 5 which are preferably formed from sheet metal and curved so as to provide channels 6 to receive the ends 7 of the standard 3, as is illustrated to advantage in Figure 1. These brackets are 95 disposed off center for a purpose which will become evident from a consideration of the operation of the device hereinafter set forth.

A pair of sleeves 8 are provided on the bottoms adjacent each end of each track way in 100 spaced relation to each other as is indicated to advantage in Figure 4. These sleeves receive the leg apparatus C. Each leg apparatus consists of a standard 9 having a foot 10 at one end and an angular extension 11 at 105 its other end receivable in the outermost sleeve 8. A sleeve 12 is disposed on the standard 9 and provided with an eye lip 13.

A brace bar 14 having angularly extending terminals 15 one penetrating the eye lip 13 110 and the other the innermost sleeve 8, holds the standard 9 at substantial right angles to

the track ways. The brace bar 14 may be easily removed by being pulled from engagement with their eye lips 13 and sleeve 8 so that the standard 9 may be pivoted toward the track way so that the latter may be rocked to inclined position.

In using the device when the same has been set up as is shown in Figures 1 and 2 the brace bars 14 to the left of the figures 10 would be removed and the track inclined. The automobile would then be run up the track ways and after having reached a certain point the track ways would automatically rock to a horizontal position that is so 15 that the leg apparatus to the right would be rested on the floor. The other leg apparatus could then be placed in its proper position and the car is ready for inspection or any other desired work. When the car is in this 20 position it is preferable that the chock devices D be used. Each of these devices consist of a U-shaped member 20 having a T-shaped handle and wheel engaging member 21 thereon. The U-shaped member engages the track way as is illustrated to advantage in Figure 6 and the T-shaped member is engaged by the wheel thus preventing movement of the vehicle when on the track way. When it is desired to remove the car 25 30 from the track way the leg apparatus C to the right would be swung by removing its brace bar so that the track way would take the dotted line position shown in Figure 1 because of the weight of the vehicle. The vehicle would then readily roll off of the inclined track way without the necessity of using even its own power.

The particular example of my invention which I have illustrated in detail, is light 40 in weight and construction when considered in the light of the work to be performed and yet is exceedingly strong and durable due to the strong structural steel parts used in the track way and the main supports A which

can be produced at comparatively low cost. 45

It is evident that various changes, modifications, and variations might be resorted to without departing from the spirit and scope of my invention, and hence I do not wish to limit myself to the exact disclosure hereof notwithstanding the foregoing details of description which have been presented merely for purposes of explanation and clearness with respect to which I now believe to be the preferred embodiment. 50 55

Having thus described my invention what I claim as new is:

1. As a new article of manufacture, a part to be used with an elevating device of the class described including a U-shaped member and a T-shaped member attached to one leg thereof. 60

2. An elevating device for automobiles including a pair of supports, a pair of trackways rockably mounted on the supports, leg apparatus on the ends of said trackways, said apparatus including a U-shaped standard one end of which is removably pivoted to the track way and the other end forming a foot, a sleeve on the intermediate portion 70 of the U-shaped standard and provided with an eye lip, and a U-shaped brace bar having one end receivable in the eye lip, and a sleeve on trackways adjacent each leg apparatus for receiving the other end of the 75 brace, whereby said brace may be easily removed and the leg pivoted to allow tilting of the trackway or whereby the entire leg apparatus may be easily removed from engagement with the trackways. 80

3. In combination, an elevating device of the class described including trackways, and chocks associated therewith including U-shaped engaging members and T-shaped wheel engaging members. 85

In testimony whereof I affix my signature.

WILLIAM E. MUNDAY.
